GAME BOARD

Sewall Smith, Lafayette, Calif.

Application October 27, 1951, Serial No. 17,140

Term of patent 14 years

(CL. D34—5)

To all whom it may concern:

Be it known that I, Sewall Smith, a citizen of the United States, residing at Lafayette, State of California, have invented a new, original, and ornamental Design for a Game Board, of which the following is a specification, reference being had to the accompanying drawing, forming a part hereof, wherein, the single figure is a perspective front face view of a game board showing my new design.

Various areas of the drawing of the board are lined for different colors.

The rear of the game board is of conventional appearance.

I claim:

The ornamental design for a game board, substantially as shown and described.

SEWALL SMITH.
